MANUALLY OPERATED PRESSURE TOOL

Filed April 10, 1937

UNITED STATES PATENT OFFICE

2,113,087

MANUALLY OPERATED PRESSURE TOOL

John Jensen, Rockford, Ill., assignor to Whitney Metal Tool Company, Rockford, Ill., a corporation of Illinois

Application April 10, 1937, Serial No. 136,151

3 Claims. (Cl. 140—113)

The invention relates to manually manipulable pressure tools such as splicing tools for wire, sheet metal shears, punches, and the like.

The general object of the invention is to provide an improved device of the class described which includes a free-running antifriction gearing capable of extremely large force multiplication.

A more specific object of the invention is to provide an improved splicing tool adapted to effect a pronounced flow of metal in the connector sleeve in clamping the same to the associated wires.

Further objects and advantages of the invention will become apparent as the following description proceeds and the features of novelty which characterize the invention are pointed out with particularity in the claims annexed to and forming a part of this specification.

For a better understanding of the invention reference may be had to the accompanying drawing in which

Figure 1 is a side elevation partly in section of a splicing tool embodying the invention.

Fig. 2 is an enlarged fragmentary vertical transverse section along the line 2—2 in Fig. 1.

Fig. 3 is an enlarged fragmentary vertical transverse section along the line 3—3 in Fig. 1.

Fig. 4 is an enlarged fragmentary horizontal transverse section along the line 4—4 in Fig. 1.

Referring more particularly to the drawing, the invention in its exemplary embodiment has been shown for purposes of illustration as applied to a portable wire splicing tool having a pair of cooperating mating dies 10—11 for clamping successive portions of a tubular connector 12 about the abutting ends of wires 13—14 (Fig. 4). It will be understood by those skilled in the art, however, that mechanisms embodying the invention may also be adapted for a wide variety of other forms of dies and metal forming tools as well as other devices. The mechanism herein illustrated includes in general a supporting structure for the dies 10—11 and a novel form of antifriction gearing designated generally by the numeral 15 which may be manually manipulated to exert an extremely heavy pressure on the dies, this pressure being of the order of 35 tons or more. The particular form of dies illustrated is adapted to carry out an improved method of wire splicing to fashion a novel form of splice. Neither the method of forming this splice nor the completed article forms any part of the present invention but is described and claimed in my copending application Serial No. 149,414 filed June 21, 1937.

The supporting structure for the dies 10—11

preferably includes a pair of relatively movable jaws which may be detachably secured together on opposite sides of the dies to form a strong rigid support during the splicing operation and which may then be swung to open position to facilitate ready removal of the spliced wire. Thus, upon reference to Fig. 1, it will be seen that the die 10 is dovetailed in a supporting block 16 slidably mounted on wear plates 17—18 in a U-shaped yoke 19 forming one supporting jaw while the die 11 is dovetailed on the face of a second jaw or link 20 pivotally connected to one of the arms of the yoke 19 by a pivot pin 21. The yoke 19 has a base plate 19a formed on the lower side thereof which may be utilized to secure the same in position. The supporting block 16 for the die 10 is restrained against sidewise movement through splined connections formed by ribs 22 and 23 on the inner faces of the arms of the yoke 19 fitting within complementary grooves in the wear plates 17 and 18, respectively. A detachable connection between the upper end of the link 20 and yoke 19 is formed by a second link 24 pivoted at its inner end in the bifurcated end of the upper yoke arm by a pin 25 and secured to the link 20 by a removable slip pin 26. It will thus be seen that when the link 20 is swung to the vertical position shown in Fig. 1 and the slip pin 26 inserted into the registering openings in links 20 and 24, a strong rigid support is formed for the dies 10—11. After the die forming operation has been completed the slip pin 26 may be removed and the link 20 rotated in a counterclockwise direction to facilitate easy removal of the spliced wire. Upon reference to Figs. 1 and 4 it will be seen that the dies 10 and 11 are respectively held in position against lateral displacement by die retaining clips 27 and 28.

The antifriction gearing 15 is adapted to selectively move the die 10 toward and away from the die 11 and comprises in general a pair of telescoping members having a series of balls engaging both members to form the equivalent of a smooth running screw thread therebetween. In the particular construction illustrated these members comprise a rotatable spindle 29 and a telescoping sleeve 30 positioned in a cylindrical housing 31 formed in the base of the yoke 19. A dog screw 32 (Fig. 2) bearing against a flattened surface 33 formed on the side of the sleeve 30 prevents rotation of the sleeve in the housing. Complementary spiral grooves 34 and 35 are formed on the adjacent surfaces of the spindle 29 and sleeve 30, respectively, and are adapted to receive a series of balls 36. The balls thus posi-

tioned in the spiral grooves formed in the sleeve and spindle constitute a free running antifriction equivalent of a screw thread between these telescoping members. Annular end plates 37 and 38 having graphite packings 39 and 40 therein are detachably secured to opposite ends of the sleeve 30 and prevent the entrance of dirt or other foreign matter into the screw mechanism. An annular shoulder 30^a in the housing 30 abuts 10 against an annular flange 31^a on the sleeve 31 to prevent outward movement of the sleeve.

In accordance with one aspect of the present invention, an improved arrangement is provided for preventing jamming of the balls 36 as they 15 approach the ends of the spiral grooves during the rotation of the spindle 29. In general, an arrangement is preferably provided for ejecting the balls as they approach one end of one of the spiral grooves and returning them to the opposite 20 end thereof. Thus, upon reference to Figs. 1 and 3, it will be seen that as the spindle 29 is rotated in a clockwise direction (as viewed in Fig. 3) the balls 36 are directed upwardly from the spiral grooves 34 and 35 by the curved inner face 41 of 25 a dog 42 into a transfer passage 43. This transfer passage is formed by a groove in the upper side of the sleeve 30, its upper side being closed by the housing 31. The dog 42 is illustrated in the form of a pin inserted in the sleeve 30 and 30 arranged generally tangentially to the base of the spiral groove 34 formed in the spindle 29. As the rotation of the spindle continues, the balls move through the transfer passage 43 to the outer end thereof from which they are directed by a second 35 dog 44 (Fig. 2) having a curved inner face 45, back into the cooperating spiral grooves. When the spindle 29 is rotated in the opposite direction the balls progress through the spiral grooves and back through the transfer passage 43 in the 40 opposite direction. It will thus be seen that a smooth free running equivalent of a screw thread is had in which the possibility of jamming of the balls at the end of the spiral tracks which carry them is obviated.

An arrangement of the type described in which 45 the balls in the spiral grooves are prevented from jamming by ejecting the same at the end of their path of travel in the grooves is particularly 50 adapted for use in a splicing tool such as that herein disclosed or other devices in which the retractive movement of the operating members is not impeded by the work piece. Thus, in the 55 splicing tool hereinbefore described, the die 18 may be freely retracted after compressing the connector sleeve 12 without sticking due to its contact with the sleeve. As a result, there is no 60 jarring effect on the balls 36 which would cause them to be loosened. Consequently, they are likely to become jammed and flattened after 65 continued use if some arrangement is not provided for ejecting them from the end of their path of travel in the spiral grooves. In the case of punch presses and similar mechanisms, however, the retractive movement of the punch or die is 70 impeded by its frictional contact with the metal through which it is passed so that it pulls free with a jerk. This uneven movement ordinarily serves to loosen the balls in the spiral grooves so that in such instrumentalities it is frequently 75 unnecessary to use such an ejection arrangement as is herein set forth.

The inner end of the spindle 29 is operatively connected to the supporting block 16 for the die 18 by a pair of cap screws 46 fitted in opposite 75 sides of an annular groove 47 formed in the inner

end of the spindle. It will be noted upon reference to Fig. 4 that the upper one of the cap screws 46 also serves to hold the die retaining clips 27 in position. As the spindle 29 is rotated by a suitable manual operating handle 48 connected thereto by a socket 49 the die supporting block 16 and its attached die 18 are thus moved toward or away from the cooperating die 11, depending upon the direction of rotation of the spindle.

In the operation of the mechanism described above, the tubular connector sleeve blank 12 is slipped over the adjacent ends of wires 13 and 14 which are to be spliced together and the connector is then positioned between the dies 10-11. The link 20 is swung to its vertical position shown in Fig. 1 and the slip pin 26 inserted so as to maintain the dies in alignment during the clamping operation. The die 10 is then moved toward the die 11 to bring the same into clamping engagement with the connector sleeve 12 by rotating the manual operating handle 48. It will be noted that upon reference to Fig. 4 that the active faces of the dies 10-11 are adapted to cover only a relatively small portion of the length of the connector sleeve so that the clamping operation is repeated a number of times throughout the length of the sleeve in order to clamp it in position on the wires. In view of the antifriction gearing arrangement utilized it is possible to exert an extremely heavy pressure of the order of 35 tons or more on the dies even though the mechanism is merely manually manipulated. As a consequence, a substantial flow of metal in the connector sleeve may be effected so that a very strong splice is had. In fact, it has been found that when using such a mechanism with properly shaped dies, a splice can be formed which has a tensile strength greater than that of the wires which are joined together.

Although a particular embodiment of the invention has been shown and described in some detail for purposes of illustration, there is no intention to thereby limit the invention to this particular embodiment but, on the other hand, the appended claims are intended to cover all modifications within the spirit and scope of the invention.

I claim as my invention:

1. A splicing tool device of the class described comprising, in combination, cooperating relatively movable metal forming compression die members, screw means associated with said metal forming members for exerting an extremely heavy clamping pressure thereon by manual manipulation including two members arranged in telescoping relation with each other and a series of balls engaging both of said telescoping members to form the equivalent of a smoothly running screw thread therebetween, at least one of said telescoping members having a spiral groove therein receiving said balls, and means for ejecting the balls from between said telescoping members as they approach the ends of said groove to prevent jamming thereof.

2. A splicing tool device of the class described comprising, in combination, cooperating relatively movable metal forming compression die members, screw means associated with said metal forming members for exerting an extremely heavy clamping pressure thereon by manual manipulation including two members arranged in telescoping relation with each other and a series of balls engaging both of said telescoping members to form the equivalent of a smoothly running screw thread

therebetween, at least one of said telescoping members having a spiral groove therein receiving said balls, and means including a transfer passage disposed exteriorly of said groove for shifting the balls from one end of said groove to the other to prevent jamming thereof.

3. A portable splicing tool for compressing a generally tubular connector about the abutting ends of a pair of wires to be spliced, comprising in combination, a pair of mating dies adapted to receive a portion of the connector therebetween, a yoke having its arms disposed on opposite sides

of one of said dies to form a sliding support therefor, a link pivotally connected to one of the arms of said yoke and forming a support for the other of said dies, and screw means associated with said dies for exerting a strong clamping pressure thereon by manual manipulation to cause a substantial flow of metal in the connector including two members arranged in telescoping relation with each other carried by said yoke and a series of balls engaging both members to form 10 the equivalent of a screw thread therebetween.

JOHN JENSEN.
